CLAIM

The ornamental design for a portion of a display screen with icon, as shown and described.

DESCRIPTION

FIG. 1 is a front view of portion of a display screen with icon showing my new design; and,

FIG. 2 is a front view of the portion of a display screen with icon of FIG. 1, in which a mobile terminal in broken lines is provided to illustrate an example environment.

The broken line immediately adjacent the solid-line portions of the design is for illustrative purposes only and forms no part of the claimed design. The broken line drawing of the mobile terminal shown in broken lines in FIG. 2 is for illustrative purposes only and forms no part of the claimed design. The size, scale and position of the icon for a portion of a display screen of FIG. 2 is for illustrative purposes and forms no part of the claimed design.
